UNITED STATES PATENT OFFICE.

JOHN MEHL, JR., OF JERSEY CITY, NEW JERSEY.

DESIGN FOR A COVER FOR POCKET-BOOKS OR CARD-CASES.

SPECIFICATION forming part of Design No. 28,170, dated January 18, 1898.

Application filed December 14, 1897. Serial No. 661,899. Term of patent 3½ years.

To all whom it may concern:

Be it known that I, JOHN MEHL, Jr., a citizen of the United States, residing at Jersey City, in the county of Hudson and State of New Jersey, have invented and produced a new and original Design for the Covers of Pocket-Books or Card-Cases, of which the following is a specification, reference being had to the accompanying drawings, forming a part thereof, in which—

Figure 1 is a plan view of a pocket-book or card-case cover embodying the features of my design, and Fig. 2 is a longitudinal section on the line 2 2 of Fig. 1.

The leading feature of the design consists in depressed or intaglio delineations, which form a diamond panel A at the center of the cover, quadrantal corner-panels B, and segmental panels C and small diamond panels D between the corner and the central panels. At each side of the center of the cover a duplicate grouping of lines appear depressed or in intaglio, the detail arrangement of the lines being as follows: At each side of the center of an end portion of the cover segmental lines

a and *a'* are drawn, extending from the end to the opposite sides of the cover. Other segmental lines of greater radius are drawn at said end, including one line *b*, starting from the bottom of the line *a* and extending concentric with the line *a'* to the same side of the cover, another segmental line *b'* of still greater radius being started from a point near the center of the line *a* and extending concentric with the lines *a'* and *b* to the edge of the cover at which said lines *a'* and *b* terminate. Lines *d* and *d'* occupy the same relative positions to the line *a* as the lines *b* and *b'* do to the line *a'*, the line *d* starting at the base of the line *a'* and the line *d'* starting near the center of the line *a'*, both lines *d* and *d'* terminating at the same edge of the cover as does the line *a*.

I claim—

The design for the cover of pocket-books and card-cases herein shown and described.

JOHN MEHL, JR.
